TRACK-ALIGNING DEVICE

David Rich, Spooner, Wis., assignor of fifteen per cent to August J. Lemke, ten per cent to Garnett R. McKeever, and ten per cent to Clarence E. Falk, all of Spooner, Wis., and ten per cent to Edward H. Grewe, Eau Claire, Wis.

Application December 2, 1938, Serial No. 243,664

1 Claim. (Cl. 254—44)

This invention relates to new and useful improvements in devices for properly aligning the rails of a railway track.

At times, a railway track will work out of proper alignment as a result of traffic thereover, freezing of the ground, et cetera, and when this condition develops it is necessary for the track, including rails and ties, to be moved laterally until proper alignment has been restored. The present invention has for its principal object to provide means whereby a worker may quickly and successfully restore the track to proper alignment without the assistance of others.

A further object is to provide a device comprising a shoe member having an end adapted to engage securely the ballast between the ties and an end adapted to rest upon a rail of the track to be moved into alignment, said device also including lever-operated mechanism having means for engaging the rail whereby said rail and the track of which it is a portion will be moved when the lever-operated mechanism is manipulated.

Other objects and advantages will be apparent from the following description when taken in connection with the accompanying drawing in which

Figure 1 is a perspective view of the shoe member.

Figure 2 is a perspective view of the lever-operated mechanism, and

Figure 3 is a side view of the device when in use, a portion being broken away.

Referring to the drawing, the invention includes a shoe member as illustrated in Figure 1 and a lever member as illustrated in Figure 2, which members are combined to form the complete device. The shoe member, which is designated generally at 10, includes a base plate 11 having a right-angular flange 12 extending from the upper edge of its rear face. Projecting from the upper portion of the front face of the plate 11 are upwardly inclined spaced ratchet bars 13 having teeth 14 on their upper faces.

The lever member includes a rock lever 15 having its lower end bifurcated as at 16 and having its upper end of hollow construction to provide a socket for an operating bar 17. Pivotally mounted within the bifurcation 16 and depending therefrom is a pawl 18 and pivotally mounted

within the outer end of the bifurcation is one end of a rail-engaging arm 19. It will be noted that the pawl 18 is provided with downwardly extending lugs at each side whereby to engage the outer sides of the ratchet bars 13 and thereby prevent lateral displacement of the pawl. This arm 19 is provided with a hook 20 adjacent its pivotal end, and an angularly extending portion 21 at its outer or free end, said hook being adapted to receive one side of a rail head therein, while the portion 21 rests on the other side of the rail head.

When the device is to be put to use the shoe member 10 is first placed in position between the ties with the plate 11 embedded in the ballast 22 in such a manner that the flange 12 will rest on the surface of the ballast, the free ends of the ratchet bars 13 being positioned so as to rest upon the head of the rail 23 to be aligned. The lever member is then applied to the shoe member by placing the rock lever 15 between the ratchet bars 13 so that the arm 19 with its hook 20 and portion 21 will engage the rail head in the manner illustrated in Figure 3, wherein one of the ratchet bars 13 is broken away, and so that the pawl 18 will engage certain of the teeth 14. A suitable bar 17 is then placed in the socket of the rock lever 15 by means of which said lever may be rocked to force the hook 20 against the rail head and thus move the track into proper alignment.

What is claimed, is:

A railroad track-aligning device comprising a shoe member including a base plate adapted to penetrate the track ballast and having front and rear faces, spaced ratchet bars connected to and extending forwardly from the front face of the base plate, a flange extending rearwardly from the upper edge of the rear face of the base plate and adapted to engage the surface of the track ballast, a bifurcated rock lever positioned between the ratchet bars, a work-engaging member pivotally mounted in the outer end of the bifurcation, and a pawl pivotally mounted within the bifurcation inwardly of the work-engaging member and adapted to engage the ratchet bars whereby to provide a fulcrum for the rock lever.
